UNITED STATES PATENT OFFICE.

HERMANN R. BOISSIER, OF NEW YORK, N. Y.

CUT-OUT FOR ELECTRIC-ARC LAMPS.

SPECIFICATION forming part of Letters Patent No. 310,783, dated January 13, 1885.

Application filed March 5, 1883. (No model.) Patented in England January 22, 1883, No. 361; in France January 22, 1883, No. 153,254; in Belgium January 22, 1883, No. 60,234; in Germany January 24, 1883, No. 26,439, and in Austria May 9, 1883, No. 2,547.

To all whom it may concern:

Be it known that I, HERMANN R. BOISSIER, of New York city, in the county of New York and State of New York, have invented a new 5 and useful Improvement in Electric Lights; and I do hereby declare that the following is a full and exact description of the same, reference being had to the accompanying drawings, and to the letters of reference marked 10 thereon.

When a number of voltaic-arc lamps are used in one electric circuit, conditions sometimes arise which make it desirable that a lamp be cut out of the circuit, and in such 15 manner that the circuit to the remaining lamps be left intact. The condition making this desirable which is the most frequently to be remedied is a failure of the arc itself, arising either from total consumption of carbon in the 20 lamp or from failure of the feeding devices to properly feed the carbons toward each other. If such condition were not at once remedied, there would be an immediate extinguishment of all lamps in the circuit; hence, as stated, 25 when such a contingency happens, the lamp should be immediately cut out of the circuit, while at the same time the circuit to the remaining lamps is preserved.

The accomplishment of such a result is the 30 object of this invention, to which end it consists in the peculiar devices and novel arrangement of circuit-connections more particularly hereinafter described and claimed.

In carrying the invention into practice a 35 first shunt-circuit to the carbons is provided containing a hollow or axial electro-magnet and an adjustable resistance to control the relative proportion of current passing through the shunt. The core of this axial electro- 40 magnet is shorter than the length of the magnet, and, fitting loosely within it, rests at the lower end thereof when the magnet is not charged or only feebly charged. The resistance in this circuit is so adjusted that when 45 the proper distance between the points of the carbons is preserved the amount of the current passing through this first shunt and around the magnet shall be insufficient to mag-

netize it powerfully enough for it to lift its core to a central position within it. With this 50 relation existing, if the distance between the carbons be increased, causing increased resistance in the direct lamp-circuit, a greater proportion of current passes around the magnet, energizing it more strongly until, when the 55 predetermined distance apart of the carbons has been reached, enough current flows around the magnet to energize it sufficiently to lift its core, which controls a second shunt-circuit. This second shunt-circuit contains a piece of 60 fusible wire—that is, a wire which is a conductor of a feeble current, but readily heated and fused by a more powerful current. This shunt is normally broken by a lever or spring falling or springing away from a contact-point 65 or anvil, against which it is raised or pressed by the core of the magnet in the first circuit when the core is lifted by the magnet. Such closure of this second shunt-circuit is followed by the immediate fusion of the fusible wire, which 70 normally held a lever in a third shunt-circuit away from its contact or anvil, and of course upon the fusion this lever contacts with the anvil, completing the third shunt-circuit, 75 which is a plain shunt-circuit around the carbons. This general description will be better understood by reference to the drawings, in which—

Figure 1 is a diagrammatic view showing the relative arrangement of circuits and devices disassociated from the other mechanism of a lamp. Fig. 2 is a plan view showing the cut-out in position with the regulating devices of a lamp, and Fig. 3 is a top view of the cut-out.

The regulator shown in Fig. 2 is one for which I made prior application for a patent, and it is not shown or described herein, it being understood that the cut-out which forms the subject-matter of this case may be used 90 with any form of regulator.

In the drawings, 1 2 represent the main electric circuit, 1 being in connection with the carbon C, and 2 in connection with the carbon C'.

3 3 is a shunt-circuit thereto, containing an

adjustable resistance, R, and a hollow or axial magnet, M, whose core A is somewhat shorter than the magnet, and rests normally upon the bottom of the magnet or upon its base. At 5 its upper end it is provided with a projection or pin, a, upon which rests the free end of a lever, L, (which may be a spring,) included in a second shunt-circuit, 4 5, in which is also included a piece of wire, W, capable of conducting a feeble current, but which shall be immediately heated to fusion by the passage of a more powerful current. In this shunt-circuit 4 5 there is normally a break between the lever L and its contact or anvil c. 10 15 6 7 is a third shunt-circuit, in which is included a lever, D, and its anvil or contact B, a spring, S, tending constantly to press D against B, from which it is held, however, (against the stress of the spring,) by the wire W. 20 25 30 In Figs. 2 and 3 are clearly shown a mechanical construction and relation of these parts suitable for carrying the invention into effect, and which is readily understandable from the detailed description hereinbefore given. It is evident, however, that the construction of the details may be varied without departing from the spirit of the invention, which requires only that the various devices and circuits shall bear to each other the relation electrically shown in Fig. 1.

The operation of these devices is as follows: Upon the separation of the carbons to such a degree that a large resistance is offered to the current, or when one is consumed, so that 35 there is no path whatever for the current through the light-giving portion, the current is entirely or to a large degree shunted through 3 M 3, causing M to raise A to a central position within itself, whereupon the pin 40 a carries L against c, closing the second shunt, 4 W 5. This new circuit, being of little resistance relatively to 3 M 3, takes a large proportion of the current, and the wire W is immediately melted thereby, allowing D to contact with B, closing the third shunt, 6 D B 7, 45 which, being of practically no resistance com-

pared to 3 M 3, takes most of the current, and then forms a permanent shunt around C C', so that the remainder of the series is not affected by the failure of C C'. As the bit of fusible 50 wire W was held in position by the screws v v, it may readily be replaced, and should be whenever the cause of failure of the arc between C C' has been remedied.

It is to be noted that the shunt-circuit 3 M 55 3 is never broken, and that its operativeness depends simply on its resistance relatively to other circuits.

What I claim is—

1. The combination of the main circuit of 60 an electric lamp with three shunt-circuits, one containing a magnet and adjustable resistance, one containing a fusible wire, and one containing a make-and-break mechanism, each of said shunt-circuits being arranged relatively 65 to each other, substantially as shown and set forth.

2. The combination, in an electric lamp, of 70 a shunt-circuit containing a make-and-break cut-out with a second shunt including a fusible conductor and a normally-open circuit-closer, and a third shunt-circuit containing an electro-magnet all arranged substantially as described, whereby the second shunt is closed by the action of the electro-magnet due to an 75 abnormal flow of current in the third shunt, and the first shunt is permitted to close by the rupture of the fusible conductor in the second shunt, thereby establishing a path of 80 low resistance around the lamp.

3. In an electric lamp or regulator, the combination of the resistance R, hollow electro-magnet M, movable core A, lever L, contact-point c, fusible wire W, contact-point B, spring-contact D, with the necessary circuits, 85 arranged substantially as shown and described.

This specification signed and witnessed this 13th day of October, 1882.

HERMANN R. BOISSIER.
